[57] CLAIM

The ornamental design for a combined picnic table and barbecue grill, as shown and described.

DESCRIPTION

FIG. 1 is a perspective view of a combined picnic table and barbecue grill showing my design;

FIG. 2 is a top plan view of the table of FIG. 1;

FIG. 3 is a front view of the table of FIG. 1;

FIG. 4 is a bottom view of the table of FIG. 1;

FIG. 5 is a rear view of the table of FIG. 1;

FIG. 6 is a right or left side view of the table of FIG. 1;

FIG. 7 is a cross-sectional view taken along line A-A' of FIG. 2; and
FIG. 8 is a perspective view of another embodiment of the design of the present invention.

FIG. 1
